UNITED STATES PATENT OFFICE.

ALFRED L. HASTINGS AND LUCIUS M. SCOTT, OF SAN JOSÉ, CALIFORNIA.

BRUSH-CUTTING MACHINE.

SPECIFICATION forming part of Letters Patent No. 612,726, dated October 18, 1898.

Application filed October 7, 1897. Serial No. 654,360. (No model.)

To all whom it may concern:

Be it known that we, ALFRED L. HASTINGS and LUCIUS M. SCOTT, of San José, in the county of Santa Clara and State of California, 5 have invented a new and Improved Brush-Cutting Machine, of which the following is a full, clear, and exact description.

The object of the invention is to provide a new and improved cutting-machine more especially designed for cutting brush, weeds, prunings, &c., into small pieces and distributing the same over the ground to permit of conveniently plowing the pieces under for fertilizing purposes.

15 The invention consists of certain parts and details and combinations of the same, as will be fully described hereinafter and then pointed out in the claims.

Reference is to be had to the accompanying 20 drawings, forming a part of this specification, in which similar characters of reference indicate corresponding parts in all the figures.

Figure 1 is a sectional side elevation of the improvement on the line 1 1 in Fig. 2. Fig. 25 2 is a plan view of the same. Fig. 3 is a rear end elevation of the same. Fig. 4 is an enlarged rear end elevation of the cutting device. Fig. 5 is a partly-sectional side elevation of the same on the line 5 5 of Fig. 4, and 30 Fig. 6 is an enlarged sectional side elevation of the adjusting-bearing for the main axle.

The improved brush-cutting machine is provided with suitable side wheels A, mounted on an axle B and connected therewith by 35 means of a suitable ratchet mechanism, so that upon a forward motion of the machine the wheels A rotate the axle B, but upon a backward motion thereof the rotation of the wheels A will not affect the axle, which then 40 does not turn. The axle B is journaled in longitudinally-adjustable bearings C, (see Fig. 6,) held on a frame D, provided at its forward end with a tongue E for the team used in drawing the machine over the ground.

45 On the rear end of the frame D is journaled a guide or supporting wheel F, and on the top of the said frame is arranged a seat G for the driver, as plainly shown in the drawings.

Curved rake-teeth H, placed a suitable distance apart, extend with their points in a forward direction close to the ground, as plainly

indicated in Fig. 1, and the upper forward ends of the said curved rake-teeth are hung loosely on a shaft or rod H', supported on suitable brackets D', attached to the frame D. 55

Now when the machine is drawn over the ground the brush, prunings, weeds, and the like are gathered up by the rake-teeth H and travel up the same in an upward and rearward direction to finally come in contact with 60 a cutting device operating in conjunction with the rake-teeth in the rear and a suitable distance above the points of the teeth, so that the material is cut into small pieces, which drop between the rake-teeth to the ground in 65 the rear of the points of the teeth. This cutting-machine consists principally of knife-guards I and cutters or knives J, preferably made S-shaped, each pair of knives and guards being between adjacent rake-teeth, as 70 is plainly indicated in the drawings. The guards I are supported from a transverse rod I', carried in brackets I², attached to the frame D, and the knives J are secured on a transverse shaft J', journaled in suitable 75 bearings in the brackets I². (See Figs. 4 and 5.)

On the shaft J', and near the middle thereof, is secured a sprocket-wheel K, over which passes a sprocket-chain K', also passing over 80 a sprocket-wheel K², secured on the axle B, so that when the latter is rotated a rotary motion is transmitted by the sprocket-wheels K² and K and the sprocket-chain K' to the shaft J' and the several knives or cutters J, 85 so that their cutting edges operate in conjunction with the knife-guards I to shear the material passing between the guards and knives. The knives J are preferably made S shape in form, and the several knives are set 90 at angles to each other, as is plainly indicated in Fig. 5, so that the knives act successively on the brush to cut the same into small pieces.

It is understood that the knives are close to the knife-guards I, and the latter are curved 95 to insure a proper shearing of the material traveling up the rake-teeth as the machine is moved forward.

The lower ends or points of the guards I extend somewhat below the top surfaces of 100 the rake-teeth and up which surfaces the material travels, so that the material is directly

guided upon the curved edges of the guards to be cut into small pieces by the revoluble cutters or knives J.

By the arrangement described, the small pieces into which the material is cut drops between the rake-teeth down to the ground a suitable distance in the rear of the points of the rake-teeth, so that the cut pieces do not come in contact with the upwardly-traveling brush or the brush in front of the rake-teeth, and consequently the pieces are equally distributed over the ground to be in position for being plowed under for fertilizing purposes, as above mentioned.

15. Each rake-tooth H is engaged near its upper end by a loop or link L, and the several links are held on a transverse rod N, carried by a lever O, fulcrumed at O' on a bracket attached to the frame D. The lever O is curved to extend alongside the seat G, so as to be within easy reach of the driver, and on the said lever is fulcrumed a hook Q, fulcrumed on the lever O and adapted to engage with its end the rod or shaft II' at the time 25 the lever O is thrown forward and the rake-teeth are raised off the ground, so as to lock the rake-teeth in the raised position, as indicated in dotted lines in Fig. 1. By this arrangement the rake-teeth may be thrown out 30 of action at any time and locked in an inactive position.

Having thus described our invention, we claim as new and desire to secure by Letters Patent—

35. 1. A brush-cutting machine, comprising a supporting-frame, curved rake-teeth carried by said frame, a transverse rod carried in brackets secured to the rear portion of the frame, curved knife-guards supported from 40 said transverse rod and extending between the rake-teeth, a transverse shaft journaled in bearings in the said brackets, and revoluble cutters carried by said shaft and operating in conjunction with the said guards to 45 cut the brush passing up the teeth and upon the guards, substantially as described.

2. A brush-cutting machine provided with a frame having side supporting-wheels, the axle of which is journaled in longitudinally-50 adjustable bearings held on said frame, the said frame being also provided at its rear end with a guide-wheel, curved rake-teeth spaced apart and extending with their points in a forward direction close to the ground, the upper 55 ends of the said curved teeth extending upwardly and forwardly and hung loosely on a shaft supported on brackets attached to the frame, fixed knife-guards extending between the rake-teeth and located above the points 60 thereof, and revoluble cutters carried by a transverse shaft and operating in conjunction with the said guards, the said cutters being driven from the axle of the supporting-wheels, substantially as shown and described.

65. 3. A brush-cutting machine, comprising rake-teeth having their shanks curved upwardly and forwardly and independently

hinged, the points of the said teeth extending downwardly and forwardly, fixed knife-guards supported on a transverse rod and extending between the rake-teeth and above the points thereof, the lower edges of the guards being curved upwardly and forwardly and the lower ends or points of the guards extending below the top surface of the rake-teeth when the latter are in the operative position, and revoluble cutters secured on a transverse shaft journaled in the frame forward of the rod carrying the guards, the said cutters operating in conjunction with the said guards, substantially as described. 75 80

4. A brush-cutting machine, comprising curved rake-teeth having their upper ends hung loosely on a shaft or rod supported on the frame of the machine, the points of the 85 said teeth extending in a forward direction close to the ground, fixed knife-guards supported on a transverse rod and extending between the rake-teeth at the rear and above the points thereof, the lower edges of the said 90 guards being curved upwardly and forwardly from the rake-teeth and the lower ends or points of the guards extending below the top surface of the rake-teeth when the latter are in the operative position, revoluble S-shaped 95 cutters secured on a transverse shaft journaled in the frame forward of the rod carrying the guards, the said cutters operating in conjunction with the said guards to cut the brush passing up the teeth and onto the said 100 curved edges, and means for rotating the said cutters upon moving the machine forward over the ground, substantially as set forth.

5. A brush-cutting machine provided with rake-teeth mounted loosely on a shaft or rod 105 supported by the frame of the machine, loops for engaging the said rake-teeth, a lever having a rearwardly-extending member carrying the said loops, and an upwardly-extending member extending near the driver's seat, and 110 a hook fulcrumed on the said upwardly-extending member and extending rearwardly to engage the rod carrying the rake-teeth to lock the rake-teeth in position when the latter are raised off the ground, substantially as 115 set forth.

6. A brush-cutting machine provided with rake-teeth hung loosely at their upper forward ends on a shaft or rod supported on brackets secured to the frame of the machine, 120 loops for engaging the said rake-teeth, a transverse rod on which the loops are held, a lever having an approximately vertical portion extending alongside the seat, and a rearwardly-extending portion carrying the said 125 transverse rod, and a hook fulcrumed on the vertical portion of the lever and extending rearwardly to engage with its hooked end the rod on which the rake-teeth are mounted when the rake-teeth are raised off the ground, as 130 set forth.

7. A brush-cutting machine, comprising a frame provided with side wheels, upwardly-extending brackets carried by said frame, a

shaft or rod supported in said brackets, curved
rake-teeth having their points extending
downwardly and forwardly and their upper
portions or shanks extending upwardly and
forwardly, the upper forward ends of the said
teeth being hung loosely on the said shaft or
rod, knife-guards supported from a trans-
versely-extending rod, the said guards ex-
tending between the rake-teeth at the rear,
revoluble cutters operating in conjunction
with the guards and secured on a shaft jour-
naled in suitable bearings, the said shaft be-

ing located forward of the rod carrying the
guards, a sprocket-wheel secured on the said
shaft, and a sprocket-chain connecting the 15
said sprocket-wheel with a sprocket-wheel on
the axle of the side wheels, substantially as
set forth.
